UNITED STATES PATENT OFFICE.

GEORGE P. FENNER, OF NEW LONDON, CONNECTICUT.

SHEET-DELIVERY APPARATUS FOR PRINTING-MACHINES.

SPECIFICATION forming part of Letters Patent No. 352,402, dated November 9, 1886.

Application filed June 24, 1886. Serial No. 206,059. (No model.)

To all whom it may concern:

Be it known that I, GEORGE P. FENNER, a citizen of the United States, residing at New London, in the county of New London and State of Connecticut, have invented new and useful Improvements in Sheet-Delivery Apparatus for Printing-Machines, of which the following is a specification.

My invention relates to improvements in sheet-delivery apparatus adapted more especially for printing-presses; and it has for its object to provide novel and efficient mechanism for taking away the sheets from the impression-cylinder and depositing them properly on a suitable support.

The object of my invention I accomplish in the manner and by the means hereinafter described and claimed, reference being made to the accompanying drawings, in which—

Figure 1 is a side elevation of a printing-press containing my invention. Fig. 2 is an end elevation of the same, partly in section, in the plane xx , Fig. 1.

Similar letters indicate corresponding parts. The letter A designates a suitable supporting-frame.

B is an impression-cylinder, and C is a type-bed, both placed in proper relation to one another.

D is a driving-shaft, which, by means of gear-wheels D' D'', transmits motion to the main shaft E. The shaft E, by means of a crank, E', and rod E'', imparts motion to the traveling rack-wheel E'', which meshes into a stationary rack, E', Fig. 2. The rack-wheel E'' engages with a suitable rack, E'', attached to the type-bed C, and imparts a reciprocating motion to the type-bed. A rack, C', on the type-bed is suitably arranged to engage with

a cog-wheel, B', of the impression-cylinder B and to impart motion to the said cylinder B. In the case of stop-cylinder presses, a portion of this cog-wheel B' is cut away, so as to permit the type-bed C to travel while the cylinder is at rest during certain intervals. The impression-cylinder is provided with a catch or lug, F, which is adapted to be engaged by a catch-lever, F', which operates to check, hold, and start the impression-cylinder B in

any well-known manner.

In the example shown in the drawings the

catch-lever F' is properly pivoted or fulcrumed, as at f, and is vibrated or moved by a cam, F'', and a rod, F''. The rod F'' is connected at one point to the lever F, and said rod F'' has a roller-stud or other suitable appliance for engaging a suitable way of the cam F''. Part of the rod F'' is slotted or bifurcated, so as to clear the main shaft E, and is provided with a block, f''.

The impression-cylinder is provided with suitable grippers, B'', for holding the sheet to be printed upon the cylinder. The grippers B'' are operated by springs and by cams or posts B'' B'', suitably arranged in any well-known manner.

G is a rack secured to the frame A, and said rack G is engaged by a gear-wheel, I. The gear I has a shaft, I', provided with two supporting disks, reels, or wheels, K' K''. The reels or wheels K' K'' form a carriage for the reel J, and are adapted to travel back and forth or to reciprocate along suitable ways, K K. The disks K' and shaft I' support the carrier-reel J J, which is constructed to receive the printed sheet from the impression-cylinder B. The gear-wheel I is adapted to engage at proper intervals with a gear-wheel, K'', on the impression-cylinder B, so that the gear I and reel J receive a rotary motion.

The carrier-reel J J, as seen in the drawings, is formed of two disks. By making said disks adjustable toward or from one another on the shaft I' said carrier-reel J can be adjusted for varying widths of sheets.

To the main shaft E is secured a suitable cam, I'', which engages with a roller-stud, I'', on a lever, I''. The lever I'' is properly fulcrumed or pivoted, as at i'', and said lever I'' connects, by a link, I'', with the shaft I', carrying the gears I I. A rod, I'', extends through a socket, i'', on the frame of the press, and is connected to the lever I''. The rod I'' has a collar, i'', which is subjected to the action of a spring, I'', in such a manner that the roller-stud I'' of the lever I'' is continually kept in engagement with the cam I''. Other known means may, however, be employed to keep the roller-stud I'' in engagement with the cam I''.

The gear-wheel I and the disks of the carriage K' have bearings for a gripper-shaft, M', on which shaft are mounted grippers M. The

grippers M are operated by a lever, M², fulcrumed at M³ on the gear I, and subjected to the action of a spring in any well-known manner. Trip-cams M³ M⁴, suitably fixed to the device, operate the lever M² and grippers M at proper intervals. The grippers M impinge upon a suitable rod or blade, K⁴, properly attached to the gear-wheel I and carriage K', so that the edge of a sheet can be held between the grippers M and the blade K⁴. Instead of a rod, K⁴, a radial web or partition can be employed, extending from the shaft I toward the circumference of the gear I. To allow room for such partition, the disks, which in this case form the reel J, will have to be slotted. K³ is a support suitably fixed to the device, and on which support the axle I' of the reel J rests at proper intervals.

The support K³, as here shown, comprises two parts—that is, a support at each side secured to the frame A, and each slotted, one end of the slots being open, so that the ends of the reel-axle move into the slots when the carrier-reel is advanced to the impression-cylinder, and move out of said slots when the carrier-reel is moved away from the impression-cylinder.

When a sheet is to be delivered from the impression-cylinder B to the carrier-reel J, the carrier-reel is moved by the cam I² and lever I⁴ toward the cylinder B. The shaft I' passes onto the fixed support K³, as seen in Fig. 1, the gear I comes into engagement with the gear K², and the revolution of the cylinder B now causes the reel J to revolve. The grippers M of the carrier-reel J grasp the sheet on the impression-cylinder when an edge of said sheet has been passed within reach of said grippers M, and said sheet is thus taken off the cylinder B and wound onto the reel J. The reel J is then by the action of lever I⁴ moved away from the cylinder B and along the racks G and ways K K. During this movement of the reel J the grippers M are actuated at the proper time by the cam or post M³ so as to release the sheet which detaches itself from the reel J, and as the reel J passes on away from the cylinder B the sheet from the reel J comes to rest upon a table, H. During the time that the reel J is taking a sheet from the cylinder B it is well to lock the axle I' into the support or journal K³, so that the axle I' cannot accidentally pass out of the support K³ while revolving in said support. For locking the axle I' in the support K³, I provide a suitable locking device, n³. (Shown in Fig. 1 as out of engagement with the axle I'.) The locking device n³ swings about a pivot, n⁴, suitably attached to the frame, and said locking device is actuated by a rod or arm, N⁴. The rod or arm N⁴ is guided by a guide-pin or steadyng-pin, n, and said rod N⁴ receives motion from a cam, N³, on an axle or shaft, N². The main shaft E actuates the rod or axle N² by means of bevel-gears N N', suitably attached to the main shaft and to the shaft N². Said rod N⁴, by acting upon a pin or stud, n², upon

the locking device n³, will bring said locking device into and out of the locking position at proper intervals. Said rod N⁴ is also provided with a notch or stop, n', and, through means of an arm, N⁵, and shaft or axle n⁵, said rod N⁴ actuates an arm, N⁶, provided with a notch or stop similar to the notch or stop n'.

In the position shown in Fig. 1 the rod N⁴ and arm N⁶ are in engagement with pins n⁶, fixed to the carrier-reel J, or to some suitable portion of the mechanism connected with the carrier-reel—as, for example, to the gear I and to one of the disks or wheels K'. When the reel J moves toward and into engagement with the cylinder B, the rod N⁴ and arm N⁶ are in such positions as to engage the pins or stops n⁶. The result of this engagement is to secure proper revolution of the reel J after the gear I has passed out of engagement with the rack G and before said gear I has come into engagement with the gear K². As improper revolution of the reel J might derange the proper relative positions of the grippers M and B², such improper revolution is to be avoided. When the reel J is about to pass out of engagement with the cylinder B, the rod N⁴ and arm N⁶ again come into engagement with the pins or stops n⁶ and again secure proper revolution of the reel J. The cam N³ is so adjusted that during the time the gear K² actuates or revolves the gear I said rod N⁴ and arm N⁶ are out of engagement with the pins or stops n⁶. By having the reel J so arranged as to come into contact with the cylinder B during the transfer of a sheet from the cylinder to the reel, sagging of the sheet is prevented.

What I claim as new, and desire to secure by Letters Patent, is—

105

1. The combination, with the impression-cylinder, of the stationary supports K³, having open-ended slots, the carrier-reel J, having an axle, I', and adapted to be actuated by the impression-cylinder, and means, substantially such as described, for moving the reel-axle into and out of the slotted supports and to and from the cylinder.

2. The combination, with the impression-cylinder, of the carrier-reel J, a fixed support or journal, K³, for the shaft of the carrier-reel, and a locking device, n³, substantially as set forth.

3. The combination, with the impression-cylinder, of the carrier-reel J, a fixed support or journal, K³, for the shaft of the carrier-reel, and a detent mechanism, N⁴ N⁶, substantially as set forth.

4. The combination, with the impression-cylinder, of the carrier-reel J, a fixed support or journal, K³, for the shaft of the carrier-reel, a locking device, n³, and a detent mechanism, N⁴ N⁶, substantially as set forth.

5. The combination, with the impression-cylinder, of the fixed reel support or journal K³ and a carrier-reel adapted to be actuated by the impression-cylinder to receive the sheet, substantially as set forth.

6. The combination, with the impression-

cylinder, of stationary supports K^3 , the carrier-reel J , having an axle, I' , and end supporting-disks, K' , the ways K , located beneath the reel and on which the supporting-disks 5 rest and travel, and means, substantially such as described, for moving the carrier-reel to and from the cylinder and causing the reel-axle to move into and out of engagement with the stationary supports.

10 7. The combination, with the impression-cylinder and the gear K^2 thereof, of the carrier-reel J , having a gear, I , adapted to engage with the gear on the impression-cylinder, and a fixed support for the shaft of the carrier- 15 reel, substantially as set forth.

8. The combination, with the impression-cylinder, of a stationary support, K^3 , a carrier-reel, J , having an axle, I' , and means, substantially such as described, for moving

the reel-axle into and out of engagement with 20 the said support and to and from the cylinder.

9. The combination of the impression-cylinder having the attached gear K^2 , the reciprocating carrier-reel J , having a shaft, I' , provided with a gear, I , adapted to engage and 25 disengage the gear on the cylinder, stationary support K^3 , the stationary rack G , and means, substantially such as described, for reciprocating the reel and moving its shaft into and out of engagement with the said support. 30

In testimony whereof I have hereunto set my hand and seal in the presence of two subscribing witnesses.
